UNITED STATES PATENT OFFICE.

ORRELL ASHTON, DECEASED, LATE OF SWAMPSMOTT, MASSACHUSETTS, BY HANNAH ASHTON, EXECUTRIX, OF SWAMPSMOTT, MASSACHUSETTS, ASSIGNOR TO UNITED SHOE MACHINERY COMPANY, OF PATERSON, NEW JERSEY, A CORPORATION OF NEW JERSEY.

SHOE-IRONING APPARATUS.

1,244,405.

Specification of Letters Patent.

Patented Oct. 23, 1917.

Application filed February 17, 1916. Serial No. 78,931.

To all whom it may concern:

Be it known that ORRELL ASHTON, late of Swampscott, in the county of Essex and State of Massachusetts, deceased, invented 5 certain Improvements in Shoe-Ironing Apparatus, of which the following description, in connection with the accompanying drawings, is a specification, like reference characters on the drawings indicating like parts

10 in the several figures.

This invention relates to apparatus for use in treating portions of a shoe after the lasting operation in order to cause the shoe materials to conform more closely to the shape 15 of the last and to prepare the shoe for subsequent manufacturing operations, and more particularly to ironing apparatus by the use of which the materials may be rubbed and pressed in the presence of heat to shape them 20 as required.

In the manufacture of some types of shoes, such as McKay shoes and welt shoes, in which the upper materials must to some extent be folded or plaited over the margin 25 of the innersole at the toe and the heel in the lasting operation, it is a matter of considerable difficulty to render the folds sufficiently flat upon the bottom of the innersole to permit a close attachment of the sole or 30 the welt, as well as to shape the upper in close conformity to the lateral surface of the last adjacent to the edge of the shoe bottom. In the manufacture of welt shoes, moreover, the folds in the upper increase 35 the difficulty of conforming the upper to the angle between the lip and the feather edge of the innersole in such manner as to insure a close attachment of the upper and the welt to the innersole lip. In order to 40 overcome these difficulties it has been found of advantage after the lasting operation to rub and press portions of the upper upon and adjacent to the margin of the shoe bottom by the use of a heated instrument. 45 Other portions of the upper also, particularly at the sides and at the top of the forepart of the shoe, are frequently treated with advantage by the use of a heated ironing tool in order to shrink and smooth the 50 leather into close conformity to the contour of the last.

It is an object of this invention to provide an ironing apparatus of improved construction arranged to permit different portions

of lasted shoes to be presented in convenient 55 position for effective treatment. Although the construction herein shown is particularly adapted for use in the manufacture of shoes of the McKay or the welt type, it will be understood that many of the features of 60 the invention are of more general application to the treatment of various types of shoes.

An important feature of the invention consists in a novel combination and arrangement of means for ironing the materials upon or adjacent to the margin of the bottom of a lasted shoe and means for ironing portions of the upper over the top of the last, constructed to facilitate the manipulation 70 of the shoe and the presentation of the shoe to the different means in succession. In the use of the construction herein shown the shoe may be presented in a substantially upright position for treatment of the materials either on or adjacent to the margin of the shoe bottom or on the top of the forepart of the last, so that the shoe may be readily transferred from one ironing means to the other; and by reason of this construction the materials on the margin of the shoe bottom, where a relatively great pressure is desirable for the purpose of smoothing and flattening the folds of the upper, may be treated to the best advantage through downwardly directed pressure on the ironing means. This arrangement, moreover, enables the operator, while presenting the shoe to the bottom ironing means, to ascertain 85 conveniently, by pressure of his thumbs upon the upper over the forepart of the last, whether this portion of the upper requires ironing to cause it to conform closely to the last, and if such ironing is found to be required the shoe may then be presented without inconvenience or loss of time to the appropriate ironing means.

The above and other features of the invention, including certain details of construction and combinations of parts, will 100 now be described with reference to the accompanying drawings and pointed out in the claims.

In the drawings:

Figure 1 is a perspective view of an apparatus in which the invention is embodied,

Fig. 2 is a view of the ironing means in transverse section, illustrating two different

positions of a shoe presented to said means, and

Fig. 3 shows in detail a portion of the means for heating the ironing device.

The apparatus, in the form shown, is adapted to be supported upon a work bench or other suitable means of support by an arm 2 secured to the bench, but the apparatus may form, if desired, a portion of a machine having means for pounding the shoe or for performing other operations thereon. The ironing means comprises upper and lower members 4 and 6 respectively, which may be formed integral but in the construction shown are separate and are secured together by screws 8 in engagement with flanges 10 and 12 on the respective members, the member 4 being secured to the arm 2 by means of screws 14. A layer 16 of asbestos or like material is interposed between the arm 2 and the member 4 in order to conserve the heat. The heating medium in the illustrated construction comprises a gas flame which is directed inwardly from a nozzle 18 on a gas supply pipe 20 through a pipe 22 that projects through an opening in the end of the member 6 into the chamber formed by the members 4 and 6. The pipe 22 is supported on a bracket 24 clamped to the pipe 20, and is open at the end adjacent to the nozzle for the admission of the air necessary to support combustion. At its inner end the pipe 22 is closed by a plug 26, and in the side of the pipe are a plurality of slots 28 to direct the products of combustion against the member 6. The heated air and gases will thus constantly fill the chamber formed by the members 4 and 6, escaping finally through outlets 30 and 32 in the respective members.

The member 4, in the construction shown, is formed to present an ironing face 34 lying substantially in a horizontal plane and having a concavely curved front edge 35, and an upright face 36 concavely curved in substantially parallel relation to the curved edge 35 of the face 34. The face 34 is thus adapted to iron the materials on the margin of the bottom of a lasted shoe and the face 36 to engage and iron simultaneously portions of the upper on the side of the shoe adjacent to the bottom edge. For ironing a McKay shoe the face 34 may be of any width desired, but in the construction illustrated this face is of suitable width to permit its front edge 35 to press the upper into the angle between the lip and the feather edge of a welt shoe innersole simultaneously with the engagement of the face 36 with the surface of the upper at the side of the shoe, as shown in Fig. 2. The faces 34 and 36, as thus disposed, are in position to facilitate greatly the ironing of the material on the bottom of the shoe, since they permit the shoe to be

pressed downwardly against the face 34 as 65 well as forwardly against the face 36, in a manner particularly convenient for the operator, and the arrangement permitting downward and forward pressure of the shoe is also of great advantage in creasing the 70 upper of a welt shoe in the angle between the feather and the lip of the innersole. The curve of the portion 34 of the device and the corresponding curve of the face 36, moreover, are of material assistance to the operator in manipulating the shoe, since these portions of the device as thus formed not only approximate the curve of the portions of the work presented for treatment and therefore engage the work effectively, but 80 also conform to the path in which it is most natural and easy for the operator to move the shoe as he swings it from side to side and turns it to bring different portions into position to be treated.

It will be observed by reference to Fig. 2 that in the shoe presented to the ironing member 4 the upper materials do not conform as closely as they should to the top of the forepart of the last. In order to 90 remedy this condition, which is sometimes met with in lasted shoes, it is desirable to rub and press the upper over the last with a heated ironing tool, and in the construction shown the tool 6 below the member 4 is provided for this purpose. This tool presents an ironing face convexly curved about a substantially horizontal axis extending longitudinally of the member 4, and as thus formed is adapted to engage 100 and iron the upper, particularly over the top of the forepart of the last. It will be apparent by reference to Fig. 2 that this arrangement facilitates the transfer of the shoe from one ironing portion of the device 105 to the other, since after treatment of the shoe by the ironing faces of the member 4 it is only necessary to lower the shoe to present it to the member 6, and that in the treatment of the top of the forepart of the 110 upper the shoe may be in a substantially upright position as in ironing the margin of the bottom. The illustrated construction and arrangement, moreover, permits the operator, while presenting the shoe for treatment by the ironing faces 34 and 36, to ascertain readily by pressure of his thumbs, which in holding the shoe will be positioned upon the upper over the top of the last, whether the condition of this portion of the 115 upper requires treatment by the ironing member 6, and if such treatment is found to be required, the shoe may then be readily and quickly presented in position to receive it.

It will be understood that except as required by the express terms of the claims the invention is not to be regarded as lim-

ited precisely to the illustrated form of the ironing faces nor to other precise details of the construction shown.

Having described the invention, what I claim as new and desire to secure by Letters Patent of the United States is:—

1. An apparatus of the class described comprising, in combination, means for ironing the materials on the margin of the bottom of a lasted shoe, said means being arranged to permit the shoe to be presented in a substantially upright position for downward pressure against the ironing means, and means below said ironing means constructed and arranged to iron the top portions of the upper on the forepart of the shoe presented likewise in a substantially upright position.

2. An apparatus of the class described comprising, in combination, an ironing device having a substantially horizontal upwardly facing ironing surface shaped for engagement with the margin of the bottom of a lasted shoe and a second downwardly facing ironing surface curved upwardly at both the front and the back of the tool to permit the top of the forepart of the shoe to be ironed with the shoe presented in a substantially upright position, and means for heating said ironing device.

3. An apparatus of the class described comprising, in combination, an ironing device having an ironing face shaped for engagement with the margin of the bottom of a lasted shoe and positioned to enable the operator to press his thumbs upon the upper over the forepart of the last to ascertain the condition of the upper with reference to the last while presenting the shoe for treatment, said device having another

face below said first mentioned face for ironing the upper over the forepart of the last, and means for heating said ironing device.

4. An apparatus of the class described comprising, in combination, an ironing device having an ironing face positioned substantially in a horizontal plane and shaped for engagement with the margin of the bottom of a lasted shoe and a second ironing face for engaging the top of the forepart of the shoe, said second face being positioned below said first named face and convexly curved about a substantially horizontal axis extending longitudinally of said first named face to permit the shoe to be presented thereto in a substantially upright position, and means for heating said ironing device.

5. An apparatus of the class described comprising, in combination, an ironing device having a portion shaped for ironing a lasted shoe adjacent to the bottom edge line of the shoe and arranged to permit a shoe to be presented in a substantially upright position for treatment, said device having another portion below said first named portion presenting a convex downwardly facing surface for engagement with the top of the forepart of the shoe with the shoe presented in a substantially upright position, the two portions of the tool being constructed and arranged to provide an interior heating chamber, and means for directing a gas flame into said chamber.

In testimony whereof I have signed my name to this specification.

HANNAH ASHTON,
Executrix of the will of Orrell Ashton.
